His Attorney.

UNITED STATES PATENT OFFICE

JAMES E. KILZER, OF ST. LOUIS, MISSOURI, ASSIGNOR, BY MESNE ASSIGNMENTS, TO DAVIS BORING TOOL COMPANY, OF ST. LOUIS, MISSOURI, A CORPORATION OF MISSOURI

EXPANSION BORING TOOL

Application filed February 13, 1928. Serial No. 253,874.

This invention pertains to boring tools of the expansion type.

One of the objects of this invention is to provide a boring tool of simplified construction, which will be cheap to manufacture and at the same time capable of accurate adjustment.

Another object is to provide a construction which will operate with reduced wear on certain parts.

Another object is to provide improved means for moving the cutters for adjustment.

Another object is to provide improved means for locking the cutters in adjusted position.

Further objects will appear from the following description, taken in connection with the accompanying drawing, in which—

Figure 1 is a longitudinal section of a boring bar embodying this invention, taken on line 1—1 of Figure 2;

Figure 2 is a transverse section, taken on line 2—2 of Figure 1;

Figure 3 is a perspective view of the wedge block;

Figure 4 is a view similar to Figure 3, showing the wedge block for use in inverted position; and

Figure 5 is a view similar to Figure 2, but on a reduced scale, showing the inverted wedge block in use.

Referring to the drawing, 1 designates the boring bar, which may be of any suitable design, and is provided with a transverse slot 2, in which the cutters 3 are adapted to move to adjustment. The transverse slot 2 is intersected at the center of the bar 1 by a transverse or radial cylindrical bore 4. Fitted to move longitudinally in the bore 4 is a wedge block or bushing 5.

The wedge block 5 is generally cylindrical in shape, as shown in Figures 3 and 4, but has a portion thereof cut away to provide a series of wedging surfaces 6 adapted to engage correspondingly beveled surfaces 7 on the rear of the cutters 3. The portion of the bushing 5 not cut away provides a pair of fins 8. These fins 8 are adapted to fit snugly within guide slots 9 in the cutters 3. One of the fins 8 is provided with a slot 10 therealong adapt-

ed to receive the projecting end of one or more pins 11, which project into the bore 4 at a suitable point to properly position the wedge block in the bore. The wedge block is provided with a thread 12 extending centrally therethrough.

An adjusting screw 13 is provided with an enlarged head 14 having a flange 15 adapted to fit an annular seat at the outer end of the bore 4, as shown in Figure 2. The other end 60 of the screw 13 has a portion thereof reduced in diameter to provide a journal 16. The reduction of diameter provides a shoulder 17 adjacent this journal. At the inner end of the bore 4 a socket 18 is provided to receive 65 the journal 16 and to form a bearing therefor. The head 14 is circular in form and is surrounded by a ring retainer 19, which is threaded into the boring bar 1 and provides an abutment for the flange 15.

In order to retain the cutters 3 in adjusted position, a locking pin 20 is provided for each cutter. The pins 20 are inserted into suitable sockets in the bar 1 adjacent the cutters 3 and running transversely thereof. The 75 upper ends of these pins are provided with threaded portions 21 engaging a similar thread in the upper end of the socket. That portion 22 of the pin 20 which comes opposite the cutter 3 when the pin has been properly inserted is turned eccentric with and smaller than the body of the pin. The sockets in which these pins are seated are positioned so as to intersect the slot 2 in such a way that when the pin 20 is turned, the eccentric portion 22 will bind against the cutter 80 to lock the same in position.

In the construction shown in Figure 2, the cutters are moved by turning the screw 13 right-handedly in the usual manner to force 90 the cutters 3 outwardly to a greater diameter. As it has been established as a standard for boring tools of this type that the adjusting screw is turned right-handedly in order to expand the cutters, this arrangement 95 will require a left hand thread on the screw 13. The retaining ring 19 provides an abutment to take up the thrust of the screw during the expanding operation. This ring is securely held by being threaded into the bor- 100

ing bar. After being adjusted in place, this ring may be peened over at its edges so as to retain it securely in position.

It will be noted that in this device the adjusting screw 13 is maintained accurately in its central position by bearings at both ends thereof. This insures accuracy in the travel of the wedge block 5. The fins 8 also act as guides in the slots 9 so as to guide the movement of the cutter, keeping the rear end central, in the slot 2 and avoid binding of the same.

It will be noted that the wedge block 5 may be used in either upright or inverted position. In the position of Figure 5, the block is shown in inverted position, and in this case it moves upwardly during expansion of the cutters. This construction requires a right-hand thread on the screw 13. It will be noted that the same cutters may be used with either of the constructions of Figures 2 or 5, since the rear ends of the cutters must be beveled both ways to make them interchangeable. In the construction of Figure 5, the lower end of the screw has a thrust bearing at the shoulder 17 against the boring bar at the inner end of the bore 4. In this figure the heavy thrust comes at this end and the reduced extent of the thrust bearing at this end reduces the amount of wear at that point.

It will be noted that by threading the pins 20 into their sockets, provision is made both for securing them in their sockets and for permitting rotation of the same in order to lock and unlock the cutters. In assembling the device, the pins 20 are first screwed into their proper position and then turned so as to move the eccentric portion 22 away from the cutter, after which the cutter may be inserted in its slot. This is necessary on account of the fact that the sockets for the pins 20 intersect the slot 2 and with the cutters in place the full-sized ends of the pins could not be inserted past the cutters.

It will be seen, therefore, that this invention provides a simple and rugged construction for an expansion boring tool. The number of parts has been reduced to a minimum. All guides and bearings are in the boring bar itself, rather than in separate bearings or bushings or the like, all of which introduce inaccuracies into the adjustment of the tool.

It is obvious that various changes may be made, within the scope of the appended claims, in the details of construction without departing from the spirit of this invention; it is, therefore, to be understood that this invention is not limited to the specific details shown and described.

Having thus described the invention, what is claimed is:

1. An expansion boring tool, comprising, a boring bar having a transverse slot therein and a transverse bore intersecting said slot, a cutter movable in said slot, a wedge block

guided in said bore and having a guiding fin, said cutter having a slot adapted to receive said fin, and means for moving said block, whereby to move said cutter.

2. An expansion boring tool, comprising, 70 a boring bar having a transverse slot therein and a transverse bore intersecting said slot, a cutter movable in said slot and having a recess in its inner end, a wedge block having a guide member engaging the wall of 75 said bore to guide the block and engaging said recess to guide said cutter, said block also having a wedge member engaging said cutter to move the same, and means for moving said block along said bore.

3. An expansion boring tool, comprising, a boring bar having a transverse slot therein and a transverse bore intersecting said slot, a cutter movable in said slot and having a recess in its inner end, a wedge block having 85 a guide member engaging the wall of said bore to guide the block and engaging said recess to guide said cutter, said block also having a wedge member engaging said cutter to move the same, means for moving said block along said bore, and a locking pin threaded into said bar adjacent said cutter and undercut to form an eccentric portion adapted to lock said cutter.

In testimony whereof I affix my signature 95 this 10th day of February, 1928.

JAMES E. KILZER.
